BY John Wiedersheim

ATTORNEY.

UNITED STATES PATENT OFFICE.

JAMES W. IVORY, OF PHILADELPHIA, PENNSYLVANIA.

DENTAL CERVIX-CLAMP.

SPECIFICATION forming part of Letters Patent No. 474,131, dated May 3, 1892.

Application filed August 2, 1890. Serial No. 360,752. (No model.)

To all whom it may concern:

Be it known that I, JAMES W. IVORY, a subject of the Queen of Great Britain, residing in the city and county of Philadelphia, State 5 of Pennsylvania, have invented a new and useful Improvement in Dental Cervix-Clamps, which improvement is fully set forth in the following specification and accompanying drawings.

- 10 My invention relates to a dental cervix-clamp; and it consists of a frame with a jaw at the center thereof and a flexible tongue guided on said frame opposite to said jaw and projecting toward the same.
- 15 It further consists of a frame with screws thereon, a flexible jaw, and an opposed jaw intermediate of said screws.

Figure 1 represents a perspective view of a dental cervix-clamp embodying my invention. 20 Fig. 2 represents a face view thereof. Fig. 3 represents a section on line xx , Fig. 2.

Similar letters of reference indicate corresponding parts in the several figures.

Referring to the drawings, A designates a 25 bow or arched frame, with a jaw B at the crown thereof and screws C at the sides, forming a clamp of the order of a dental cervix-clamp.

D designates an extension of the frame opposite to the jaw B, the same forming guides 30 for the sliding head E, to which latter is swiveled a screw F, which is fitted to a cross-bar G of the extension D.

Connected with the inner end of the head E 35 is a tongue H, of flexible metal or other suitable material, which projects toward the jaw B, and being so disposed that when said jaw is in position at one side of the tooth the tongue is at the opposite side adjacent to the 40 gum, and is free to be pressed against said gum and move, shift, or slip the same for external marginal cavities or other operations requiring such movement of the gum.

The frame A is suitably bowed, so as to fit 45 over adjacent teeth, and when the jaw is located the screws C are operated so as to clamp the frame in position. The screw F is then rotated, whereby the tongue H is advanced against the relative tooth and then pushed 50 along the tooth in such manner as to press

against the gum and move or shift the same, (see dotted lines, Fig. 3) so as to uncover or expose a marginal cavity or for other purposes, after which said tongue may be further advanced by the operation of the screw, 55 thus controlling the portion of the gum with which the tongue is in engagement.

The jaw B bears against the back of a tooth intermediate of the teeth, with the faces of which the screws C are in contact, thus holding the device firmly in place without clamp-contact with the sensitive portion of the teeth, also preventing tilting of the clamp, as well as retaining it in position by action independent of the tongue H, as the latter is held in 65 contact with the tooth by the pressure of the screw F, but not bearing unnecessarily upon the sensitive cervix of the same.

Having thus described my invention, what I claim as new, and desire to secure by Letters 70 Patent, is—

1. A frame with a jaw at the center thereof, in combination with a tongue of flexible material, which is guided on the frame opposite to said jaw and projects toward the latter, forming an improvement in dental cervix-clamps, 75 as set forth.

2. A dental clamp consisting of a frame with screws fitted therein to hold the same in position, and a flexible jaw and an opposed jaw 80 intermediate of said screws, substantially as described.

3. A dental clamp consisting of a frame having arches with screws fitted therein to hold said clamp in position on the tooth, an adjustable flexible jaw, and a stationary opposed jaw, 85 said jaws being intermediate of said screws, substantially as described.

4. A dental clamp consisting of a frame having arches with screws fitted therein to hold 90 said clamp in position on the tooth, and a stationary integral jaw, a flexible jaw carried by a sliding head, and means for adjusting said head, said jaws being intermediate 95 of the screws in said arches, substantially as described.

JAMES W. IVORY.
